UNITED STATES PATENT OFFICE.

HARRY H. MARRIOTT, OF KANSAS CITY, MISSOURI.

LENS.

1,416,109.

Specification of Letters Patent. Patented May 16, 1922.

Application filed June 11, 1920. Serial No. 388,392.

To all whom it may concern:

Be it known that I, HARRY H. MARRIOTT, a citizen of the United States, residing at Kansas City, in the county of Jackson and 5 State of Missouri, have invented a new and useful Lens, of which the following is a specification.

The device forming the subject matter of 10 this application is a lens, adapted to be used in the making of signs of that sort which is illuminated from the rear.

The invention aims to improve the construction of the lens generally and, particularly, to improve the means whereby the 15 lens is connected with the plate which carries the lens and constitutes a part of the light box.

With the above and other objects in view, which will appear as the description proceeds, the invention resides in the combination and arrangement of parts and in the details of construction hereinafter described and claimed, it being understood that, within 20 the scope of what is claimed, changes in 25 the precise embodiment of the invention shown can be made without departing from the spirit of the invention.

In the accompanying drawings:-

Figure 1 shows in front elevation, a lens 30 constructed in accordance with the invention; Figure 2 is a rear elevation of the lens; Figure 3 is a side elevation wherein the lens and plate are shown; Figure 4 is a rear elevation showing the lens and the plate, 35 the parts being disposed as they will appear whilst the lens is being inserted through the opening in the plate; Figure 5 is a side elevation, parts being broken away, the view depicting the lens as it will appear whilst it 40 is being inserted through the opening in the plate; Figure 6 is a diagrammatic view illustrating the relations existing between the opening in the plate and sundry parts of the lens; and Figure 7 is a fragmental 45 sectional detail illustrating the relation existing between one of the lugs on the lens, and the plate.

The lens forming the subject matter of this application preferably is made of glass 50 and is of tubular form, the lens comprising a body 1 having a rearwardly extended reduced neck 2 defining a shoulder 3, the

neck being circular in cross section. The neck 2 is reduced in diameter as indicated at 4, and terminates in a tapered part 5. In 55 the end of the part 5 of the neck there is a groove 6 which may be lined with quick silver, as indicated at 7 for the purpose of reflecting the light forwardly. A crescent shaped fin 8 projects from the neck 2, parallel to the shoulder 3. Lugs 9 project from the neck 2 and are disposed approximately opposite to the ends of the crescent shaped fin 8, the lugs having slanting outer surfaces 29. 60

The numeral 10 marks a plate, adapted to constitute a part of a light box or the like, the plate having a circular opening 11 conforming in diameter to the diameter of the neck 2. 65

In practical operation, the lens is tilted, as shown in Figure 5, and the neck 2 is inserted through the opening 11 in the plate 10, the fin 8 passing behind the plate. The lens is then swung in the direction of the 75 arrow A in Figure 5. The slanting surfaces 29 of the lugs 9 first distort the plate 10, as indicated at 50 in Figure 4. The lugs 9 ultimately pass through the opening 11 and then the material of the plate, which 80 was distorted as indicated at 50 springs back into alignment with the remaining portions of the plate, as indicated in Figure 7. It will be seen that the lens is now held by the lugs 9 and the fin 8 in the opening 11 of the 85 plate 10.

Having thus described the invention, what is claimed is:-

A sign-forming element comprising a body having a reduced neck defining a shoulder, the neck being provided with an outstanding crescent-shaped fin disposed parallel to the shoulder, and being equipped with outstanding lugs disposed approximately opposite to the ends of the fin, those 90 surfaces of the lugs which are remote from the shoulder slanting toward the neck. 95

In testimony that I claim the foregoing as my own, I have hereto affixed my signature in the presence of two witnesses.

HARRY H. MARRIOTT.
